BATHING AID SPONGE

Dale W. Rowley, Firesteel, S. Dak.

Filed Mar. 5, 1963, Ser. No. 73,831

Term of patent 7 years

(Cl. D9—2)

FIG.4

FIG.5

FIG. 1 is a front elevational view of a bathing aid sponge showing my new design;

FIG. 2 is a side elevational view thereof;

FIG. 3 is a rear elevational view thereof;

FIG. 4 is a top plan view thereof; and,

FIG. 5 is a bottom plan view thereof.

What I claim is:

The ornamental design for a bathing aid sponge, substantially as shown.
